[57] CLAIM

The ornamental design for a remotely activated switch module for controlling power usage of an appliance, as shown and described.

DESCRIPTION

FIG. 1 is a top, front and left perspective view of a remotely activated switch module for controlling power usage of an appliance showing our new design; FIG. 2 is a bottom, rear and right perspective view thereof;

FIG. 3 is a front elevational view thereof;

FIG. 4 is a rear elevational view thereof; and

FIG. 5 is a top plan view thereof, the bottom plan and side elevation views being identical.

The broken lines shown in FIGS. 1 and 3 are for illustrative purposes only.
